UNITED STATES PATENT OFFICE.

ANSON J. BENTLEY, OF NILES, AND FRANK F. BENTLEY, OF WARREN, OHIO.

BRICK-PALLET.

1,140,104.

Specification of Letters Patent. Patented May 18, 1915.

Application filed October 26, 1914. Serial No. 868,783.

To all whom it may concern:

Be it known that we, ANSON J. BENTLEY and FRANK F. BENTLEY, citizens of the United States of America, residing at Niles, Ohio, and Warren, Ohio, respectively, and doing business at Niles, in the county of Trumbull and State of Ohio, have invented certain new and useful Improvements in Brick-Pallets, of which the following is a specification.

Our invention relates to improvements in brick-pallets of the kind shown in our Letters Patent No. 833665, October 16th, 1906, and No. 859039, July 2nd, 1907; and the objects of our invention are:—To retain the levelness of the pallets during transportation of the bricks to and from the rack driers; to keep them apart while lying on the cars; to permit a free circulation of air between the bricks on the pallets; and to provide a reversible pallet with convenient grasping edges or handles.

With these and other objects in view the invention consists in the novel details of construction or combination of parts more fully hereinafter disclosed and particularly pointed out in the claims.

Referring to the accompanying drawings forming a part of this specification in which like numerals designate like parts in all the views:—Figure 1 is a perspective view of a brick pallet made in accordance with our invention; Fig. 2 is a longitudinal sectional view of the parts shown in Fig. 1; and Fig. 3 is an enlarged perspective view of one corner of the pallet, illustrating the handle thereof.

1 represents the body portion of the pallet, which is formed by cutting away the metal of a sheet along the edges 3 to leave the four projecting portions or edges 2. The metal 4 associated with said projecting edges 2 is next bent at an angle to the body 1 as indicated at 5, and said metal rolled up on a former, or by other means, into the tubular shape shown, thus constituting a substantially closed tube integral with and extending across, the body portion 1 of the pallet. That portion of the rolled metal 4 which extends beyond the edges 3 of the body portion 1, form convenient grasping ends or handles 6, while the body portion 1 extends in the

direction of a diameter of said rolled handles 6, so that the latter will always maintain said body portion above the supporting surface 7 of the pallet as will be clear from the drawings. Not only do the rolled handles 6 maintain the body portion 1 above the support 7 and thus afford a space for the free circulation of air between said body portion and support, but the extensions or handles 6 provide another space between the edges 3 of adjacent pallets, which permits a circulation of air in a direction at right angles to that afforded by said first mentioned space.

It is an important feature of our present invention that the body portion 1 extends diametrically of the rolled handles 6 as above stated, and that the edges 3 are cut away thus leaving two smooth unobstructed surfaces on said body 1, for these features enable the pallet to be readily reversed and either side of the body 1 used at will. This latter feature is often of importance when the said body becomes warped or bent for a reversal of the pallet then tends in use to straighten it; and further by omitting the turned over edges 2, 2' of our Patent No. 1064811, June 17, 1913, we provide a freer circulation of air under and between the pallets. It is in these important particulars that the present invention differs from that of our said Patent No. 1064811.

What we claim is:

1. A reversible pallet having a flat body portion having two unobstructed flat surfaces and two cut away side edges; and a rolled handle portion integral with and extending across each end of said body portion, each of said handle portions also extending beyond each side edge, and above and below each flat surface of said body portion, whereby said pallet may be readily reversed in use, substantially as described.

2. A reversible brick pallet comprising a metal sheet having a body portion with flat surfaces cut away at the sides leaving unobstructed edges and providing extensions on either side thereof; and said extensions being bent at an angle to said body portion and formed into a tube extending beyond each flat surface of said body portion, substantially as described.

3. A reversible brick pallet comprising a body portion having two flat unobstructed surfaces and cut away side edges combined with integral hollow rolled handle members extending beyond said side edges, and also beyond said flat surfaces, substantially as described.

In testimony whereof we affix our signatures in presence of two witnesses.

ANSON J. BENTLEY.
FRANK F. BENTLEY.
